UNITED STATES PATENT OFFICE.

THOMAS RUBINO, OF HAZLETON, PENNSYLVANIA.

DESIGN FOR A CLOTHES-LINE TROLLEY.

SPECIFICATION forming part of Design No. 31,554, dated September 26, 1899.

Application filed August 30, 1899. Serial No. 729,014. Term of patent 14 years.

To all whom it may concern:

Be it known that I, THOMAS RUBINO, of Hazleton, in the county of Luzerne and State of Pennsylvania, have invented and produced a new and original Design for a Clothes-Line Trolley, of which the following is a full, clear, and exact description.

Reference is to be had to the accompanying drawing, forming a part of this specification, in which the figure is a perspective view of a clothes-line trolley, showing my design.

The design in its entirety consists of a plate A approximately rectangular in shape, with slots B B' starting at one side of the plate and

diverging inwardly in upward and downward directions, the upward slot B terminating in a portion B² approximately parallel to the sides of the plate.

The leading feature of the design consists in the plate with the diverging slots. 20

I claim—

The design for a clothes-line trolley herein shown and described.

THOMAS RUBINO.
